Application March 13, 1956, Serial No. 571,357

4 Claims. (Cl. 340—258)

This invention relates to a sensory aid device which automatically signals to a user in the absence of normal vision to warn him of a sharp decline in the terrain over which he is moving. The invention is useful for traveling in darkness or for a blind person to warn him of the presence of a dangerous decline such as an embankment, a cliff or a flight of stairs.

The complete apparatus including the necessary power supply means together with the necessary optical and electrical elements are desirably encased in a small portable housing. Its power supply may be lightweight batteries of the primary type or the rechargeable type. The apparatus is conveniently carried by a handle preferably on the top portion of the casing. A small electric lamp and a narrow beam reflector are mounted on the casing to project radiant energy in the direction in which the user is moving. Means are provided to scan the beam in such a manner that it will periodically traverse a path in front of and along the direction of travel. Optical means are provided to intercept and focus light reflected from a small spot on the terrain at a position between the forward and back extremity of the scanned area. The point at which the reflected light is intercepted should be vertically separated a substantial distance from the beam of the light source. The focused image of this spot is directed upon a light sensitive cell whose output is applied to the grid of an electron tube to bias the tube to cutoff when light from the beam is reflected to the cell. If a sharp decline in the terrain is encountered a shadow will be cast between the spot and the light source. When this occurs the cell is not energized and the bias on the grid of the tube is shifted to cause plate current to flow. The output of the tube is then utilized to actuate an alarm thus warning the user of the presence of the decline.

The principles of the invention are presented herein in connection with a specific application but the invention may be embodied in other apparatus of a similar nature defined by and within the scope of the appended claims.

It is a primary object of the invention to provide a device to automatically energize an identifiable alarm by sense of touch or hearing thus to give warning to the user of a dangerously sharp decline in his path.

It is a further object of the invention to provide a step-down indicating means wherein the signal is derived from a beam of light functioning in connection with an electro-optical sensing means.

A further object of the invention is to provide indicating means of the above indicated type which is self-powered and light in weight.

A further object of the invention is to provide a step-down detecting means capable of discriminating against the operating signal and signals originating from other ambient sources to radiant energy.

Other objects and features of the invention will more fully appear from the following description and will be particularly pointed out in the claims.

To provide a better understanding of the invention a

2

particular embodiment thereof will be described and illustrated in the accompanying drawings in which

Fig. 1 is a side elevation of the apparatus with portions of its casing broken away.

Fig. 2 is a diagrammatic illustration showing the functional interrelation of certain of the components of the apparatus.

Fig. 3 is a detail schematic illustration of a combined circuit interrupting device and beam scanning means.

Fig. 4 and 5 are diagrammatic views showing the path of the radiant energy in the operation of the device.

Referring to the drawings, particularly to Fig. 1, the complete apparatus is shown inclosed in a casing 6 which is small in size, light in weight and readily carried by the user. The apparatus is provided with a radiant energy beam scanning means which is situated within the casing desirably in the lower forward portion thereof. Any suitable means may be used to create and scan the beam. Such a means is shown partially diagrammatically in Fig. 3 of the drawings and comprises a small electric lamp 7 mounted at or near the focus of a narrow beam reflector 8. The lamp and the reflector provide a beam of light 9 which is projected forwardly and downwardly in front of and along the path of the person carrying the device. The lamp and reflector are mounted upon a member 10 of magnetic material which constitutes the armature of an electromagnet 12. The member 10 is supported upon a fulcrum 13 and is provided at its end opposite the fulcrum with an insulated contact member 14 which coacts with a second insulated contact member 15, the two contacts providing a circuit interrupting switch.

Since it is desired that the vibrator mechanism function at a certain frequency such as 30 cycles per second and that the armature travel a certain distance, suitable adjustments are provided to coact with the mechanical and magnetic characteristics of the device to obtain the desired result. The chief mechanical and magnetic factors are the operating strength of magnetic attraction of the armature to the magnet, the weight of the armature assembly, the extent of desired movement of the armature and the tension of the spring type fulcrum 13 or other spring return device. The adjustments may be of any suitable construction such as the set screw 16 which may act in conjunction with the contacts 14 and 15 which in turn may be bent or otherwise moved into a desired position to obtain the desired adjustment. Other means may be employed to scan the beam 9.

The lamp, the reflector and their support 10 together with the magnet 12 are positioned to project the beam of light forwardly in the direction in which the user is moving and downwardly at the required angle to sweep the beam along the terrain for a distance of about five to seven feet in front of the user. The lamp 7 is provided with power from any suitable source such as by a battery 17 the flow of power thereto being controlled by a switch 18. The battery is also connected to the contact member 14. The circuit thru the lamp is completed thru a ground connection. The contact 15 is connected to a coil 19 wound upon a core 20 which constitutes the electromagnet 12. The other terminal of the coil 19 is connected to ground.

When the switch 18 is closed battery current flows in the coil 19 which magnetizes the core 20 and attracts the armature 10 breaking the contact between the members 14 and 15 to open the circuit to the coil thus demagnetizing the magnet. The tension of the fulcrum member 13 then moves the armature again into circuit closing position at which time the cycle is repeated. A satisfactory operating frequency has been found to be 30 cycles per second. Any suitable frequency may be used, however. Thus while the apparatus is in use the beam is scanned along the terrain in the path of the user at the specified

frequency rate and along the specified scanning distance. Desirably, the lamp and reflector are situated inside the lower section of the front wall 21 of the casing 6. An aperture 22 is provided to allow the passage of the light beam.

Operation of the apparatus depends upon the detection of light reflected from a small area 23 situated along the path of the user and coinciding with the area scanned by the light source. Such detecting means desirably is situated within the upper portion of the casing 6 and comprises a plane mirror preferably mounted on top of the casing at its forward portion and disposed at an angle to reflect light from the area 23 vertically downward. A lens 25 is positioned below the mirror and serves to concentrate the light reflected from the spot 23 upon a small photocell 26. The power of the lens and the size of the sensitive area of the cell determine the area of the spot 23.

For most efficient operation in detecting step-down conditions in the traveled terrain the separation of the light source and the point at which the reflected energy is received should be as large as possible. As will be apparent by reference to Fig. 5 of the drawings the ability of the device to reach into the shadow area cast by the edge of the declining terrain is dependent upon the angle of the reflected beam with respect to level ground. This angle should be as great as possible otherwise the incident energy may not be cut off by the decline of the surface or may be only partially cut off thus impairing the efficiency of the device.

The manner of supplying power to the various units of the apparatus is not to be restricted to the specific circuits and elements described herein. A suitable means is provided for supplying the relatively high direct current plate circuits of the electronic devices such as the photocell, the switching tube and the amplifier tubes which are used in the apparatus. Such high voltage may be derived partially from the magnetic beam scanning device which also provides a source of pulsating current. This pulsating current is taken from the magnet winding 19 and is fed to a transformer and rectifier unit 27 thru a connection 28. The unit 27 contains a step-up transformer and a rectifying device together with suitable current smoothing elements. The output of the unit 27 is fed to the various components as indicated diagrammatically in Fig. 2.

The photocell 26 receives its operating energy from the source 27 and since, as will appear hereinafter, the cell receives a series of successive reflections from the scanned light beam its output is pulsating at the frequency of each half cycle of the scanning frequency which in the special case described herein would be 60 cycles per second. The output of the cell may be fed directly to an amplifier and thence to a relay to control an alarm device. It has been found, however, that for operation of the device under most conditions of ambient light such as sunlight the cell output desirably is fed to a filter 29 which freely passes the output of the cell at the operating frequency and discriminates against other radiant energy which may reach the cell 26. The output of the filter is fed to an amplifier 30 the output of which is, in turn, rectified in the rectifier 31 and is then fed to the grid of a switching tube 32.

So long as the photocell receives a signal the grid of the tube 32 is maintained at cut off bias and no signal is transmitted to the user. When the signal to the cell is cut off, in a manner to be explained hereinafter, the bias on the tube 32 shifts to a value which permits the tube to conduct and thence acting thru timing devices 33 and 34 energizes the relay 35 which closes a circuit 36 leading from the coil 19 of the magnetic interrupter to an alarm device 37. The device 37 desirably is in the form of a solenoid having a coil 38 within which is received an armature 39 which in turn is mechanically coupled to a carrying handle 40 on the casing 6. Since the current flowing in the circuit 36 is pulsating a vibration is set up in the handle 40 and is felt by the user.

Figs. 4 and 5 of the drawings illustrate diagrammatically the manner in which the device functions in use. In Fig. 4 the device is shown as being transported over level terrain having no step-down or sharply declining areas.

5 In such case the traversed light beam moves between the lines 40 in an uninterrupted path in front of the user who is traveling in the direction of the arrow. The optical system including the mirror 24, the lens 25 and the cell 26 are so positioned that light from the spot 23 approximately midway of the traverse of the beam is reflected to the cell 26 each time the beam passes the spot. Extraneous light reaching the cell tending to produce a false signal is stopped by the filter 29.

15 Fig. 5 illustrates a different condition; namely, that which is encountered when the user approaches a decline in the terrain. In the illustration such a decline is indicated as a flight of steps. At this time the spot 23 from which the signals originate is in the shadow of the step with respect to the scanning beam. The cell 26 therefore receives no signal and the bias on the tube 32 is shifted to the conducting region resulting in actuation of the alarm to warn the user.

20 In the latter case the alarm timing unit 34 functions to maintain the signal in operation until level terrain is again reached. The timing device may be of any suitable construction such as a conventional interval timer which is adjusted to open and close the relay 35 at any desired time interval such as every .3 to .4 of a second.

25 If a shallow decline is encountered where the signal to the photocell is interrupted only momentarily the timing device 33 acts to close the relay for a period of time which distinguishes from the time period of the timer 34. For instance, the time period of the device 33 may be three-fourths of a second after which the alarm shuts off.

30 Any suitable power supply may be used for heating the cathodes of the various tubes employed in the apparatus. Such a power supply may be a low voltage battery or any suitable source not shown. Suitable switches not shown are provided for controlling operation of the device. It should be understood that the specific circuit and use of the elements as described above are presented as an example of the application of the invention. Other arrangements and circuits may be used within the spirit and scope of the claims.

35 It should be pointed out that the use of the term radiant energy is intended to relate to the type of energy represented by the visible, infra-red, or ultra-violet spectrum. The special characteristics of such energy should be to sharply define a shadow cast by an object in its path. 40 Some forms of energy are not suitable since they would be only partially effective in distinguishing between an irradiated area receiving energy directly from a source, from an area immediately adjacent that area but screened by an intervening object which creates a shadow.

45 The device of the invention is highly efficient in detecting stepdown conditions and may readily be combined with apparatus for detecting and outlining obstacles.

50 - What is claimed is:

1. A portable sensory aid device comprising an electromagnetic vibrator having a moving armature, a radiant energy source having means to project a narrow beam therefrom, said light source being secured to and moving with said armature, means on said magnetic vibrator to maintain a substantially fixed operating frequency of vibration, a pivot to guide said armature to swing in a plane positioned to scan the beam from said light source upon an elongated area in front of the user, a radiant energy sensitive cell, means above said energy source acting to direct beam energy reflected from a selected portion of said scanned area to said sensitive cell, a warning alarm and electronic switching means connected between said cell and said alarm acting to cut off said alarm when the cell receives reflected light from the scanned area and to actuate the alarm when no reflected signals are received.
2. A portable sensory aid device comprising a carrying

case having a handle, means for projecting a beam of radiant energy upon the path in front of the user, automatic means to scan said beam forward and backward along the said path, a radiant energy sensitive cell, means a substantial distance above said beam projecting means acting to direct beam energy reflected from a portion of the scanned area to said cell, a magnetic solenoid, a pulsating power source, a relay operable to connect said solenoid with said pulsating power source, electronic switching means connected between said cell and said relay operable to actuate said relay into closed circuit condition when said cell has no output, mechanical coupling means from the armature of said solenoid to said handle whereby a warning is given to the user when a decline in his path of travel cuts off reflected signals to said cell.

3. A portable sensory aid device comprising means to project a beam of radiant energy in front of the user, automatic means to scan said beam forward and backward along the path of the user, said scanning means having a fixed scanning frequency, a radiant energy sensitive cell, means a substantial distance above said beam projecting means acting to direct beam energy reflected from a portion of said scanned area to said cell, a frequency filter connected to the output of said cell adjusted to pass the frequency of the signals reflected from said scanned area and reject other frequencies, a warning alarm having a source of power, a relay for controlling said alarm, connections from the output of said filter to the input of said relay whereby the operation of the alarm is controlled by radiant energy signals reaching the said cell reflected from said scanned area to the exclusion of radiant energy signals reaching the cell from other sources.

4. A portable sensory aid device comprising power supply means, means for projecting a beam of radiant energy energized from said power supply, means for

scanning the beam from said projecting means forward and backward in front of the user, said scanning means having an electromagnet, a movable armature actuated by said magnet and upon which said projecting means is secured, means on said armature acting to interrupt power supplied to said magnet during each cycle of movement of said armature whereby the armature is vibrated which results in scanning said energy beam, a radiant energy sensitive cell, means above said beam scanning means for directing beam energy reflected from a portion of the scanned area to said cell, an amplifier connected to the output of said cell, a warning alarm, a relay connected to the output of said amplifier, a circuit from the coil on said electromagnet thru said alarm and to the control contacts of said relay whereby pulsing current to said alarm is controlled by the output of said cell, a high voltage direct current source having a step-up transformer and rectifier, connection from the magnet of said electromagnetic scanning means to the primary of said transformer and connections from the output of said high voltage source to the elements of the apparatus requiring such voltage.
